UNITED STATES PATENT OFFICE

CHARLES E. LUCKE, OF NEW YORK, N. Y., ASSIGNOR TO FULLER LEHIGH COMPANY, OF FULLERTON, PENNSYLVANIA, A CORPORATION OF DELAWARE

FURNACE

Application filed August 7, 1928. Serial No. 297,955.

This invention relates to a novel form of furnace and will be best understood from the following description and the accompanying drawings. In the drawings, in which I have 5 shown selected embodiments of the invention;

Fig. 1 is a vertical sectional view through a furnace and boiler showing my invention applied thereto.

10 Fig. 2 is a horizontal sectional view through the furnace shown in Fig. 1, and showing my invention in diagrammatic form applied to the furnace.

Fig. 3 is a vertical sectional view through 15 the slag-tapping opening.

Fig. 4 is a detailed view illustrating one form which the heating element may take.

Fig. 5 is a fragmentary sectional view 20 through the furnace floor showing the type of heating element illustrated in Fig. 4.

Fig. 6 shows in fragmentary form a different 25 form of heating element.

Fig. 7 is a view corresponding to Fig. 5, and showing the form of heating element 30 illustrated in Fig. 6.

In operating a furnace using a slag-forming fuel, it has been suggested that the floor of the furnace should support a bed of slag in a molten condition, into which the slag 35 in the fuel may fall from the combustion chamber or into which it may flow from the walls of the chamber. The object of the invention is to insure that the slag shall remain in the molten condition referred to. This 40 molten condition is desirable for several reasons, one of which is that it facilitates the disposal of the slag which, when it is maintained in its molten condition, can be tapped from the furnace, thus avoiding troubles

45 which arise when it hardens. I have shown my invention as applied to a furnace having a combustion chamber 1 formed of walls comprising cooling tubes 2 and blocks 3 secured to said tubes. Above 50 the combustion chamber is shown a boiler indicated at 4 and which may be of any suitable form. The tubes 2 may be connected to the boiler and may be used to heat either water or steam as desired. For the purposes

55 of illustration, I have shown the furnace

burning pulverized coal which may be introduced into the furnace from a plurality of burners 5.

The fuel from these burners is burned in the combustion chamber and the hot gases 55 therefrom arise and pass over the boiler tubes in the usual way, but in doing so slag is usually formed and drops to the bottom of the furnace. The heat from the burning fuel may be sufficient to maintain the slag accumulating on the floor of the furnace in a molten condition, in which condition it may be tapped through spout 6. The opening in the furnace wall communicating with the spout may be normally closed by a gate 7 60 shown in Fig. 3, but omitted from Fig. 2 for the sake of clearness.

According to my invention, the floor of the furnace supports a bed 8 of refractory material which may be, and preferably is, an 70 accumulation of slag from the slag-forming fuel burned in the furnace, and I maintain this refractory material in a molten pool by supplementing the heat from the burners by heat from a plurality of heating elements 75 preferably mounted in the refractory material forming the floor. I shall hereinafter refer to this refractory material as slag.

The heating elements referred to may conveniently be made in the form of electrical 80 resistance elements 9, and in Figs. 4, 5, 6 and 7, I have shown two forms which such elements may take. In Figs. 4 and 5 I have shown a carbon tube 10 forming one electrode of the element, the other electrode being formed by a carbon rod 11 disposed in the tube 10. Between the two electrodes is disposed a suitable electrical resistance such as granular or pulverized carbon 12. In 85 Figs. 6 and 7 I have shown a refractory tube 13 filled with granular or pulverized carbon 14 forming an electrical resistance between electrodes 15 disposed at opposite ends of the tube.

In both forms, the electrodes are formed 95 with suitable connections 16 indicated diagrammatically in Fig. 2 as being connected to opposite sides of a line 17, which leads to any suitable source of electrical power.

By the above arrangement, the heat of the 100

burners may be supplemented to a sufficient extent to maintain the bed of slag on the floor 18 in a molten condition. As pointed out above, it is desirable to have the slag 5 in such a condition that it may be readily tapped from the furnace, and the heating elements provide any additional heat which may be necessary to bring the slag to a molten condition which will permit tapping.

10 The heating elements are particularly useful when the furnace is not running at its maximum temperature, and/or when the slag has a high fusing temperature. The heating elements will normally be used only for short

15 intervals, when it is desired to tap the slag, and then the current may be turned off. If desired the bed 8 may be previously deposited on the floor, or the slag formed by burning the fuel may be permitted to accumulate and 20 thus form the bed.

Moreover, the current may be supplied to the heating elements when the furnace is first started up, in order to help in quickly raising a furnace to the proper temperature for combustion, and then it may be turned off if or 25 when the temperature can be maintained sufficiently high by the heat from the burning fuel alone.

The amount of heat furnished by the elements 9 is small in relation to the amount of 30 heat supplied by the furnace, and it is only used at intervals and for relatively short times. Therefore, it is possible to employ electric heating elements with economy.

35 I claim:—

1. In combination, a furnace having a bed 40 of slag on the floor thereof, means to burn fuel in said furnace, and electrical heating elements adapted to heat said bed substantially throughout its extent.

2. In combination, a furnace having a substantially horizontal bed of refractory material, means to burn a fuel in said furnace, and additional means to heat said bed substantially throughout its extent.

45 3. In combination, a furnace having a bed of refractory material, means to burn a fuel in said furnace, and heating means disposed in said bed and adapted to bring it to a molten condition.

50 4. In combination, a furnace having means to burn a slag-forming fuel and having a substantially horizontal bed on the floor thereof formed at least in part by the slag 55 from said fuel, and means in addition to the burning means to heat said floor substantially throughout its extent.

5. In combination, a furnace having a bed 60 of slag on the floor thereof, means to burn fuel in said furnace, and electrical heating elements disposed in said bed.

6. In combination, a furnace having a bed 65 of slag on the floor thereof, means to burn fuel in said furnace, electrical heating elements disposed in said bed and comprising

carbon electrodes, and an electrical resistance disposed between said electrodes.

7. In combination, a furnace having a bed of slag on the floor thereof, means to burn fuel in said furnace, and electrical heating elements disposed in said bed and comprising a tube having a resistance disposed therein.

8. In combination, a furnace having a floor 70 constructed to support a bed of slag, means to burn a slag-forming fuel in the furnace, and electrical heating means arranged to heat said bed.

CHARLES E. LUCKE.
